UNITED STATES PATENT OFFICE.

MORRIS M. SHORE, OF NEW YORK, N. Y.

TELEPHONE INDEX.

Application filed January 20, 1928. Serial No. 248,252.

The present invention relates to a telephone index or directory of the type which comprises a suitable number of cards, each provided with a lettered index tab and so mounted upon a support that any one of the index cards can be displayed when reference is to be made to the names and telephone numbers thereon.

The main object of the present invention is to provide a telephone index of the type mentioned in which the several cards are pivotally mounted within a case and are adapted to be swung from the latter when the reading matter thereon is to be displayed.

Another object of the invention is to so construct the case that it may be readily attached to a telephone instrument.

A further object of the invention is to provide a connection between the cards and the case which permits the individual cards to be conveniently mounted upon and removed from said case.

A still further object of the invention is to provide transparent envelop-like receptacles for the individual cards of the index, thereby preventing soiling of the cards and also permitting replacing of the cards without discarding the envelops.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

A few of the many possible embodiments of the invention are illustrated in the accompanying drawings, in which:-

Figure 1 is a side elevation of the top portion of a telephone instrument having the improved index mounted thereon; Fig. 2 is a front elevation of said index with one of the cards swung out of the case thereof; Fig. 3 is a section taken on line III-III of Fig. 2; Fig. 4 is a front elevation of a modified construction; Fig. 5 is a side elevation of the said modification; Figs. 6 to

8, inclusive, are enlarged details of construction of the modification illustrated in Figs. 4 and 5; Fig. 9 is a front elevation of a further modification of the invention. Fig. 10 is a top plan view of the device shown in Fig. 9; and Fig. 11 is an elevation of a modified index card.

Referring now first to Figs. 1 to 3, inclusive, of the drawings, the numeral 12 indicates a desk-type telephone instrument of the well known construction. To this instrument is attached, by a spring clip 13, an index case 14, the latter comprising, in the embodiment illustrated, a bottom portion 15, from which rise sides 16. The clip 13 is attached to the front side of the case, as appears from the several figures referred to. The bottom portion 15 projects beyond the sides of the case, as indicated at 17 in Figs. 2 and 3 of the drawings. In the case 14 is mounted a suitable number of index cards 18, each of which is provided with a lettered index tab 19. The means for attaching the cards to the case comprises a screw bolt 20, which extends horizontally through the sides 16 of the case adjacent one of the lower corners thereof. With this bolt co-operates a nut 21 of any suitable construction. Each of the cards is provided with a perforation 22, through which the said bolt extends. As appears from Fig. 2 of the drawings, the tabs 19 of the cards project all above the front side 16 of the case, the several tabs being disposed in two rows and the tabs of each row being staggered so that all of the same are exposed to view. The perforations 22 are provided in the cards adjacent one of their lower corners, and obviously all of the same are in alignment so that the screw bolt may be extended therethrough.

Normally the cards are all held within the case. If reference is to be made to the printed matter displayed on any one of the same, the card is taken hold of by its tab and turned 90° on the screw bolt into the position shown in Fig. 2 of the drawings. When a card is brought into the position mentioned, one of its edges rests on the bottom extension 17 adjacent the screw bolt, the said extension forming a ledge to support the card and also a stop for limiting the outward movement of the card.

The construction illustrated in Figs. 4 to 8, inclusive, of the drawings differs from

the one above described mainly in that provision is made for attaching and detaching any one of the index cards to the case without withdrawing the pivot bolt from the latter. In this instance a pin 23 may be permanently fixed to the case. The index cards 18' are each provided with an open slot 24, extending from their lower edges 25 at an acute angle to one of the side edges 26 thereof. Each slot terminates in a substantially semi-circular portion 27, for engagement with the pin 23, and has a somewhat contracted portion 28 below the said semi-circular portion. When the index cards are disposed within the case, they rest with their lower edges 25 on the bottom 15 of the case, as shown in Fig. 6 of the drawings, and the slots extend at an acute angle to the said bottom. The cards may be shifted around the pivot pin 23 in the same manner as the cards illustrated in the construction shown in Figs. 1 to 3 of the drawings, the contracted portions of the slots preventing accidental disengagement of the cards from said pivot pin. If it is intended to remove a card from the case, the said card is shifted into the position shown in Fig. 8 of the drawings, in which its slot extends substantially horizontally. The card may then be moved in the direction of the arrow shown in Fig. 8, its material yielding sufficiently to permit the contracted portion of the slot to ride over the pivot pin. In order to insert a card, its slot is brought into horizontal position in alignment with the pivot pin and the card forced in a direction opposite to the arrow shown in Fig. 8 of the drawings as far as the slot permits.

If found necessary, clips 29 may be attached to one of the sides of the case, and in alignment with the said clips there may be provided an opening 30 in one of the extensions 17 of the bottom. These clips serve to hold a pencil or like instrument upon the case with its point 31 seated in the perforations 30. There may also be mounted a pad holder 32 on the case for receiving either loose sheets or a pad 34 of paper.

The modification illustrated in Figs. 9 and 10 differs from those above described mainly in that its pad holder 35 is in the form of a spring plate 36, which may be made integral with the rear side of the case. In this instance said case comprises also an

end plate 37 to prevent the pad from falling 55 out.

Each index card may be placed into a transparent envelop-like container 38, to prevent the card from being soiled and to permit the card to be conveniently replaced. 60 The container is somewhat larger than an individual index card, as shown in Fig. 11 of the drawings, and the perforations 22' are provided in the envelop-like containers 65 only.

What I claim is:—

1. A telephone index comprising a casing including a bottom and front and rear sides rising therefrom, a pin extending through said casing adjacent one of its lower corners, a plurality of index cards adapted to rest on the bottom of said casing between said sides, each card being provided with a slot through which said pin is extended whereby said cards are adapted to be swung around said pin, an extension on said bottom adjacent said pin forming a ledge on which said cards are adapted to rest when swung out of said casing, and a clip on said casing for attaching the same to a telephone instrument, the slot in each card extending from that edge of the card which rests on said bottom when the cards is disposed within the sides of said casing upwards at an acute angle to said edge, the slot in each card being provided with a contracted mouth portion to prevent accidental disengagement thereof from said pin. 70 75 80 85

2. A telephone index comprising a casing including a bottom and front and rear sides rising therefrom, a pin extending through said casing adjacent one of its lower corners, a plurality of transparent envelop-like containers adapted to swing around said pin, each envelop-like container being provided with an index tab disposed above said casing when the container is located within said casing, an extension on said bottom adjacent said pin forming a ledge on which said envelop-like containers are adapted to rest when swung out of said casing, and a clip on said casing for attaching the same to a telephone instrument. 90 95 100 105

Signed at New York, in the county of New York, and State of New York, this 24th day of December, A. D. 1927.

MORRIS M. SHORE.
